ELECTRON TUBE IN A RETARDING
FIELD CIRCUIT

Fritz Schröter, Berlin, Germany, assignor to
Telefunken Gesellschaft für Drahtlose Tele-
graphie m. b. H., Berlin, Germany, a corpora-
tion of Germany

Application January 28, 1933, Serial No. 654,091
In Germany March 23, 1932

2 Claims. (Cl. 250—27)

The present invention is concerned with the
retarding field circuit arrangement comprising a
thermionic tube. It is known that circuit ar-
rangements comprising tubes operating with re-
tarding fields may be carried into practice in
such a way that the sum total of the currents
flowing to the grid acting as the plate and to the
retarding electrode represent the saturation cur-
rent of the filament, and that solely the changes
in current distribution between these electrodes
are utilized. An arrangement of this kind as
known in the prior art is shown in Fig. 1.

One difficulty, however, in the attempt to in-
sure full utilization is that even above the sat-
uration potential E_g , the current exhibits a slight
additional growth with increase of potential.
The situation is illustrated in Fig. 2 graphically
in which the voltage E_g acting at the grid (ab-
scissae) is plotted against the sum total of the grid
and plate currents (ordinates). The curve there-
plotted refers to the constant plate potential E_a .
The value of the saturation voltage is represented
by the point E'_g .

In order to be able to fully utilize the current
distribution, operation is restricted to the use of
cathodes which evidence a saturation defined in
the foregoing sense.

A similar current voltage characteristic as the
one shown in Fig. 2 is found for tubes which op-
erate with screen grids maintained at a constant
positive potential. A characteristic of this sort is
shown in Fig. 3. If, while all other potentials are
maintained unvaried, the plate potential E_a of such a tube be raised beyond a certain critical
value E'_a which lies somewhat above the poten-
tial of the screen grid, then the current I_a flowing
to the plate will be found to rise only slightly.
It is easy to represent for

$$\frac{dE_a}{dI_a}$$

values of several megohms without it being nec-
essary to use the saturation current of the cath-
ode.

In the case of thermionic tubes connected in a
retarding-field scheme and which are to be op-
erated in a way as hereinbefore outlined, there is
provided between the filament and the grid acting
as a plate an arrangement of additional aux-
iliary grids in such a way that for the quantity

$$\frac{dE_g}{d(I_g + I_a)}$$

the same effect is obtained as for the internal
resistance of screen grid tubes. In this expres-

sion E_g is the potential of the grid nearest the
plate, I_g is the value of the current flowing in the
aforesaid grid circuit and I_a is the value of the
current flowing in the plate circuit. A schematic
example of such a tube is shown in Fig. 4. By the
use of electron tubes in such an arrangement
conditions are no longer dependent upon a cath-
ode having a definite saturation, and this, as is
well known from practice, is hard to accomplish.
As shown in Figure 4 the inner grid is maintained
at a constant negative voltage with respect to the
cathode, the second grid at a constant positive
voltage while the adjustable battery in the circuit
of the third grid indicates broadly any means for
applying a high positive potential thereto. As
shown, the battery in the plate circuit applies a
small negative potential to the plate whereby it
repels the electrons passing through the third
grid or produces a retarding field. When used
as a transmitter tube I have found the following
voltages to be satisfactory; third grid 4,500 volts,
second grid 250 volts, first grid a few volts nega-
tive bias and the plate a negative bias voltage as
high as 50 volts, thereby producing the retarding
field for the electrons.

I claim:

1. An electron tube circuit arrangement com-
prising the combination of an electronic tube
having a cathode, a retarding field electrode, a
grid mounted adjacent said electrode, a source of
potential having its negative terminal connected
to said cathode and its positive terminal to said
grid, means for maintaining said retarding field
electrode at a negative potential with reference
to said cathode and means for maintaining the
sum of the currents to said grid and retarding
field electrode substantially constant upon
change in potential of said retarding field elec-
trode, said means comprising a second grid lo-
cated between said cathode and first named grid,
a steady source of potential having its negative
terminal directly connected to said cathode and
its positive terminal directly connected to said
second grid, a third grid located between said
cathode and second grid and means for maintain-
ing said third grid at a steady negative potential
with reference to said cathode.

2. In a device of the class described, the com-
bination of a vacuum tube having a cathode, a
retarding field electrode and a plurality of grids
located at different positions in the electron
stream between said cathode and retarding field
electrode, a source of variable potential having
its negative terminal connected to said cathode
and its positive terminal to the outer one of said

grids, a circuit connecting said retarding field electrode and cathode and including a source of potential having its negative terminal connected to said retarding field electrode, and means comprising the inner of said grids for maintaining the sum of the currents to said outer grid and retarding field electrode substantially constant

upon variation of the potential of said outer grid and a source of constant potential having its negative terminal directly connected to said cathode and its positive terminal directly connected to said inner grid.
